UNITED STATES PATENT OFFICE.

EDWARD L. ANDERSON, OF LONG BEACH, CALIFORNIA, ASSIGNOR OF ONE-FOURTH TO
EDWARD F. THERIEAU, OF LONG BEACH, CALIFORNIA.

APPARATUS FOR HYDROGENATING OILS.

Application filed March 26, 1923. Serial No. 627,637.

This invention relates to apparatus for hydrogenating oils such as crude hydrocarbons or relatively heavy hydrocarbon products, to increase their capacity or to produce from them lighter hydrocarbons of lower boiling points. The invention has for its general object the provision of process and apparatus to get, at minimum cost, a maximum production of light gravity and low boiling point hydrocarbons.

According to this invention the desired end is reached by hydrogenating the heavier and high boiling point hydrocarbons to produce lighter products; and the invention is applicable to the production of motor fuel, kerosene, distillates, and lubricating stock, all without the necessity of further refining before being marketable. The invention in its broader aspects is somewhat similar to my invention entitled "Process and apparatus for obtaining gasoline from natural gas" for which I have filed application Serial No. 597,851, on October 30th, 1922. In said application, although I have described the invention as directed most particularly to the recovery and manufacture of gasoline from natural gas; yet that invention includes the general process of combining natural gas with a heavier hydrocarbon, thereby to produce a light hydrocarbon. In that invention, as also in the present one, the combination is effected by heat and catalytic action. But the present invention, although it at least in part functions to combine natural gas with a heavy hydrocarbon, is more particularly directed to production of the light hydrocarbons from the heavier hydrocarbons on which the process operates.

Bearing in mind these preliminary statements, the present invention will now be best understood from a detailed description of a preferred form of apparatus and preferred process procedures illustrative of the invention, reference for this purpose being had to the accompanying drawings in which:

Fig. 1 is a diagram illustrating a complete apparatus for carrying on the process;

Fig. 2 is an enlarged longitudinal vertical section of the heating and catalyzing portion of the apparatus, together with a diagram illustrating the controls;

Fig. 3 is an enlarged detail section on line 3—3 of Fig. 2;

Fig. 4 is a fragmentary section on line 4—4 of Fig. 3; and

Fig. 5 is an enlarged detail section on line 5—5 of Fig. 2.

In the drawings I show at 10 and 11 an oil tank and a water tank into which suitable air pressure may be introduced through pipes 12 and 13 to maintain a steady feed pressure above the liquids in the tanks. The liquids feed out from the tanks through pipes 14 and 15 controlled by valves 16 and 17 so that the amount and proportion of the two liquids that flow into the common feed pipe 18 may be controlled. This feed pipe 18 leads into chamber 19 and in this chamber the mixed liquids, illustrated at L in Fig. 2, are preferably maintained at a level say about one-third the height of the chamber. A pipe line 20 is provided to feed natural gas into the chamber under control of a valve 21.

In chamber 19 there is a longitudinal hollow shaft 25 carrying a plurality of heating and catalyzing elements 26, one of which is shown in detail in Figs. 3 and 4. They may be in disk form and composed of spirally arranged coils 27 of bare resistance wire held between arms 27^a that, with hubs 27^b, form the frame of the elements. These frames may be made of insulating material. One end of each spiral coil may be connected by wire 28 to lead wire 29 in the shaft 25, and the other end connected by wire 30 to shaft 25 and thus through that shaft and the shell of chamber 19 to lead wire 41. The resistance coils are preferably composed of the nickel chromium alloy known as nichrome, which material has catalytic properties. In this apparatus, as in the apparatus of my co-pending application, I combine in a single element both the heating and catalytic functions, with the advantage of supplying the heat close to the catalytic element.

At the end of shaft 25 a pulley 31 is provided, typical of means of rotating the shaft, and the elements 26. These are ordinarily rotated at comparatively slow speed, say about 60 revolutions per minute.

Leading upwardly from the upper part of chamber 19 there is a standpipe 35 surrounded by heat insulation 36 and containing another heating and catalytic coil 37 of bare wire arranged as shown in Figs. 2 and 5. At the upper end of standpipe 35 there is a vapor take-off pipe 38 that leads to condenser 39, and from the condenser the condensate goes through pipe 33 to tank 34 where the

fixed gases may be separated. Although I show here only a single condenser it will be readily understood that I may utilize any suitable system of condensation, as for instance, a fractional condensation.

Current to feed the coils may be obtained from a transformer T one side of which is connected by wires 40 and 41 to one terminal of coil 37 and to ground on chamber 19 respectively. The other side of coil 37 is connected by wire 42 to a controller C which is fed from the transformer. The last mentioned side of the transformer may be connected by wire 43 with a rheostat R which is connected to wire 29 and controls the current going to elements 26.

Pyrometers P may be located at different places in chamber 19 and standpipe 35 to indicate the temperature of the liquids and vapors, and these pyrometers may be connected by wires 44 to an indicator 45.

In the operation of the apparatus oil and water are fed into chamber 19 continuously in such quantity as to keep a proper body of mixed liquid in the chamber; and the rotation of elements 26 serves to mix, and preferably to emulsify the liquids, so as to get them into intimate admixture. Of course, the same result may be had by feeding oil and water emulsion into the chamber, adding either oil or water to make the proper proportion between the two liquids.

The heating elements 26 are, for the treatment of the average run of crude oil or its heavier derivatives, maintained at a temperature of say from 600 to 800° F. and in any case high enough to cause the evaporation of the water and practically all of the oil. Whatever residue is left may be withdrawn from time to time through the plugged opening at 50. Under the influence of heat the hydrocarbons are not only vaporized but may be also to a certain extent cracked; while the water is vaporized, and under the action of heat and catalysis, is dissociated into its elements hydrogen and oxygen. These elements, under the influence of heat and catalysis react to combine with the hydrocarbon, to a certain extent at least, in chamber 19. Consequently, there passes upwardly through standpipe 35 a mixture of fixed gases and vapors from the hydrocarbons and also the gases resulting from the water vapor, together with vapors that are the products of the combinations that take place in chamber 19. In standpipe 35 the temperature of the coils is maintained typically at from about 400° F. to about 600° F.; and under the influence of heat and catalysis the remaining unsaturated hydrocarbons are supplied with hydrogen that comes from the water, and thus vapors of lighter hydrocarbons are evolved. To a certain extent this addition of hydrogen takes place with reference to all of the unsaturated hydrocarbon

vapors that pass through standpipe 35; with the result that the vapors emerging through pipe 38 are all, or at least most of them, carrying more hydrogen than they did originally, even though some of them may then carry less hydrogen than others. The final product, if condensed at one step, will have in it a mixture of hydrocarbons of different specific gravities; but not only does this final product have a larger percentage of light hydrocarbons (motor fuel, etc.) than it did originally, but also the average specific gravity of the final product is lower than the average gravity of the original substance.

In addition to nascent hydrogen being produced by the operation of heat and catalysis, the water is also to a certain extent decomposed by the electric current that flows through it between different parts of the coils and between the coils and the walls of the device, which are grounded as described.

Free carbon that may be formed in the various reactions is taken up by the oxygen to form carbon dioxide and carbon monoxide, which pass off with the other fixed gases resulting from the process. Natural gas may also be passed into the vaporizing chamber 19 where it mixes with the hydrocarbon and water vapors, this gas also supplying hydrogen for these reactions and supplying light hydrocarbons that may also be combined with the heavier hydrocarbons of the vapors. Also, if gas is introduced, this process recovers the light liquid hydrocarbons that are carried in the gas, in the same general manner as they are recovered in the invention described in my co-pending application. The apparatus here described may be operated either with liquid hydrocarbons and water or with liquid hydrocarbons and gas, or all of them; and the proportions introduced will depend largely upon the constitution of the original hydrocarbons and upon the constitution of the desired final products, as for instance, I may say that, operating on a crude California petroleum, asphalitic base, of 10° Bé. gravity, by using water in proportions about 25 per cent of the amount of oil, maintaining a temperature in chamber 19 of about 800° F. and in standpipe 35 of about 600° F., I obtain a final product of an average gravity about 26° Bé. containing approximately 18 percent of gasoline, 22 percent of kerosene, 20 percent of stove distillate, and 35 percent of lubricating stock; the remainder being heavy residue and fixed gas.

Having described a preferred form of my invention, I claim:

1. Apparatus of the character herein described, comprising a chamber adapted to contain a partial charge of liquid hydrocarbons and water, a rotatable shaft extending through the chamber, a plurality of disk like

elements mounted on the shaft and standing partially in the liquid charge and partially in the space in the chamber above the liquid level, each of said elements including a heat and catalytic element.

2. Apparatus of the character herein described, comprising a chamber adapted to contain a partial charge of liquid hydrocarbons and water, a rotatable shaft extending through the chamber, a plurality of disk like elements mounted on the shaft and standing partially in the liquid charge and partially in the space in the chamber above the liquid level, each of said elements including a heat and catalytic element; a vapor standpipe extending from the chamber, and a heat and catalytic element in said vapor standpipe; means to feed liquid hydrocarbons and water into the chamber, and a vapor take-off pipe leading from the upper end of the stand pipe to a condenser.

15 3. Apparatus of the character herein described, comprising a chamber adapted to

contain a partial charge of liquid hydrocarbons and water, a rotatable shaft extending through the chamber, a plurality of disk like elements mounted on the shaft and standing partially in the liquid charge and partially in the space in the chamber above the liquid level, each of said elements including a heat and catalytic element; a vapor standpipe extending from the chamber, and a heat and catalytic element in said vapor standpipe; means to feed liquid hydrocarbons and water into the chamber, and a vapor take-off pipe leading from the upper end of the stand pipe to a condenser.

In witness that I claim the foregoing I have hereunto subscribed my name this 16th day of January, 1923.

EDWARD L. ANDERSON.
